J. J. MERRILL

OUTLET BOX

Filed April 12, 1922

Inventor,

John J. Merrill
By L. J. Harrigan Atty

UNITED STATES PATENT OFFICE.

JOHN J. MERRILL, OF IPSWICH, MASSACHUSETTS, ASSIGNOR, BY MESNE ASSIGNMENTS, TO ELECTRIC OUTLET COMPANY, INC., OF NEW YORK, N. Y., A CORPORATION OF NEW YORK.

OUTLET BOX.

Application filed April 12, 1922. Serial No. 552,020.

To all whom it may concern:

Be it known that I, JOHN J. MERRILL, a citizen of the United States, and a resident of Ipswich, in the county of Essex and the 5 State of Massachusetts, have invented an improvement in Outlet Boxes, of which the following is a specification.

This invention relates to that type of outlets for electric conductors known as outlet boxes, and more particularly to certain improvements on, or modifications of the type of outlet shown in my pending application Serial No. 500,525, said outlet being more especially designed for what is known 15 as "old work" construction, or installation in a lath and plaster wall which has already been erected.

Prior to my invention a type of wall fixture has been designed and placed on the 20 market, known as the "Elexit" fitting, in which a base plate is mounted on the wall and is constructed and arranged so that a similar plate, which is directly attached to the fixture may be connected to the wall 25 plate by a simple inward and lateral motion, which, at the same time makes the electrical connection, thereby permitting the electric light fixture to be readily removed and replaced.

As all the electrical connections with the 30 main conductors are located between the inner and outer walls of the building, in the rear of this wall plate, the underwriters' regulations require that these connections 35 be enclosed in a fire proof, or metal chamber. It is also necessary that the wall plate be rigidly supported, not only to provide a rigid support for the fixture, but also to enable the fixture to be removed and replaced 40 as frequently as may be desired, without disturbing the wall plate.

This fitting is so designed that the wall 45 plate must be set with its back side flush with the plaster surface, and, while this result may be accomplished, and the plate rigidly supported without difficulty, when the installation is made before the lath and plaster wall is erected, so far as I am aware 50 no means for supporting the wall plate has been produced, prior to my invention which is entirely satisfactory for "old work" construction, for example;—the construction disclosed in my said pending application is not suitable for the purpose, for the reason

that the flange of the box to which the wall 55 plate of the "Elexit" fitting would necessarily be attached thereto, it would be held at such a distance beyond the plaster surface as to be un-acceptable.

An object of my invention is to produce 60 a form of outlet box for "old work" lath and plaster construction, which will possess all of the advantages of my said prior construction and will, in addition, be suitable for the "Elexit" fittings above referred to, so that 65 a rigid support for the wall plate will be provided which will support the same in the desired relation to the surface of the plaster.

When installations are made in lath and plaster construction, in some instances the 70 plaster is found to be in such a condition that it is liable to crumble under pressure, so that a firm seating would not be provided for the outer collar of my said prior device, and in this connection, a further object of 75 my invention is to provide a construction embodying the features of my said prior device in which the necessity of having the outer clamp member bear on the plaster may be avoided and suitable means may be provided for holding the outlet box, or fixture support, in the desired position with relation to the plaster surface and for permitting repair of the plaster about the wall 80 opening.

I accomplish these objects by providing a 85 form of clamp which is adapted to seat directly on the outer side of the laths, about the wall opening, from which the plaster has been removed, which is adapted to support 90 the outlet box, or fixture support in the desired relation to the plaster surface and which is also provided with a retaining flange for holding plaster of Paris in plastic 95 form, in the space from which the plaster was removed, until it hardens.

For a more complete understanding of my invention, reference is made to the accompanying drawings in which:—

Fig. 1 is a longitudinal central sectional view of the outlet box in position in a wall, 100 at line 1—1 of Fig. 7.

Fig. 2 is a sectional view at line 2—2 of Fig. 1.

Fig. 3 plan view from the lath side of the 105 wall.

Figs. 4 and 5 are respectively, sectional views on lines 4—4 and 5—5 of Fig. 3.

Fig. 6 is a plan view of the outer side of the outer clamp member.

Fig. 7 is a plan view of the outer end of the box.

- 5 In preparation for the reception of my present construction, a rectangular shaped opening is formed through the lath and plaster wall which is adapted to permit the box to be inserted freely therein, a section 70
 10 being preferably cut from one lath which is of slightly greater length than the width of the box. If the length of the box is greater than the distance between the adjacent edges of the laths, at opposite sides of the one
 15 from which the section was removed, recesses will be cut into said adjacent laths into which the end portions of the box will extend, as shown in Fig. 3, and recesses will also be cut to receive the collar connecting 80
 20 screws.

After cutting the opening through the plaster *a* and laths *b*, the plaster about the edge of the opening is removed for a distance, in practice, of about $\frac{1}{4}$ of an inch 90
 25 from the edge of the opening *b'* in the laths, so that the outer surface of the laths about said opening is exposed, forming a seat *b''* for the outer clamp member, as hereinafter described.

- 30 In the present instance the box 1 is made approximately rectangular in cross section, except that its width is somewhat greater at its middle portion than at its ends, so that the sides are slightly convex transversely, as 95
 35 shown, and the corner formed by the shorter sides and bottom is preferably rounded or beveled to provide oblique portions in which the usual "knockouts" *1^a* are formed, through which the armored conductors may be 100
 40 passed. The longer sides of the box are slightly flared at its open end to provide supporting lips *1^b* for the purpose to be explained, and ears *1^c* are formed integrally 105
 45 therewith at each end.

50 A flat sheet metal inner clamp collar 2 is provided, having an opening *2^a* therein, adapted to register with the opening *b'* in the laths and to receive the box, the width and length of said collar being such that, when it is in position on the back side of the laths, it will overlie the same to a sufficient extent to provide the necessary supporting surface.

55 Projecting flanges or lips *2^b* are formed on the collar, at each end of the opening, which are adapted to engage the edges of the uncut laths. Screw threaded holes *2^c* are also formed in the collar, at its ends and in positions somewhat to one side of the middle 110
 60 line thereof, in which the clamping screws 3 are adapted to be threaded. The sheet metal outer clamp collar 4 is similar in outline to the inner collar 2 and its opening is 115
 65 adapted to register with the opening therein. Flanges *4^a* are formed on the collar 4 at both

of the longer sides of its opening, said flanges extending outwardly therefrom nearly to the plane of the plaster surface, when the collar is in position, and being flared away from the opening to provide on the inner sides 70 thereof a seat for the box at its outer end, and, at the outer sides thereof, under cut plaster retaining flanges, as hereinafter described.

The end portions of the collar 4 are provided with slotted holes *4^b* adapted to receive the screws 3 and located in position to register with the holes *2^c* in collar 2 and they are also provided with screw threaded holes *4^c*, which are arranged at one side of the 80 middle line thereof.

The ears *1^c* of the box are provided with screw holes *1^d* arranged in position to register with the holes *4^c* of the collar 4, so that the box may be attached to the collar by 85
 screws 5. The ears *1^c* are formed by bending a small edge portion of the box outward at such a point that they seat on the collar 4, while the box is seated at its sides on the flanges *4^a* thereof. 90

When the fitting is installed, a screw 3 is preferably threaded into the collar 2, at one end, and the collar is passed flatwise, with the opposite end first, through the opening and then it is placed in position, so that its flanges *2^b* extend into the opening and hold the collar from vertical displacement in a side wall. While thus held, the collar 4 is placed in position by passing it edgewise so that the screw 3 is passed into the slot *4^b* and, 100 when in position, the screw is tightened and then the other screw 3 is inserted and tightened, so that the collars are then clamped against opposite sides of the laths, the collar 4 seating directly on the laths. The armored conductor may then be "fished" through the collars and inserted in the box 1, and clamped therein by suitable means, after which the box will be inserted in the collars 105 so that its sides seat on the flanges *4^a*. It 110 may then be securely attached to the collars by the screws 5. The space between the plaster and the flanges *4^a* is then filled with plaster of Paris 6 in plastic state, as indicated in Figs. 1, 2, 3 and 4, so that its surface is flush with plaster. 115

The parts are so constructed that, with plaster of ordinary thickness, the end of the box will be approximately flush with the surface of the plaster *a*, but under no condition will project beyond the plaster surface, so that when the wall plate of the "Elexit" filling, indicated in dotted lines in Fig. 1, is attached, it will bear on the plaster surface. This wall plate will be secured 120 in place by screws which are threaded in holes *4^d* provided therefor in the collar 4. 125

I claim:

1. In an electrical installation outlet for a lath and plaster wall having an opening, 130

a clamp comprising an inner and an outer collar adapted to engage the opposite sides of the laths about the opening and having connecting means for holding the same in 5 clamping engagement therewith, a box adapted to be inserted in said collars means carried with the outer collar for positioning the box with its outer end approximately flush with the plaster surface and means for 10 attaching the box to said outer collar.

2. An electric installation outlet for a lath and plaster wall comprising an inner collar adapted to seat on the inner side of the laths about an opening therein, an outer 15 collar adapted to seat on the outer side of the laths about said opening and having outwardly projecting, plaster-retaining flanges at opposite edges of its opening, means for clamping said collars together against the 20 laths, an outlet box and means for attaching the same to said collars.

3. An electric installation outlet for a lath and plaster wall comprising an inner collar adapted to seat on the inner side of the laths 25 about an opening therein, an outer collar adapted to seat on the outer sides of the laths about said opening and having outwardly and divergently projecting, plaster-retaining flanges at opposite edges of its 30 opening, means for clamping said collars together against the laths, an outlet box and means for attaching the same to collars.

4. An electric installation outlet for a lath

and plaster wall comprising an inner collar adapted to seat on the inner side of the laths 35 about an opening therein, an outer collar adapted to seat on the outer sides of the laths about said opening and having outwardly projecting, plaster-retaining flanges at opposite edges of its opening, means for 40 clamping said collars together against the laths, a box adapted to be inserted in said collars and provided with a surface to seat on said flanges and to be sustained thereby with the outer end of said box adjacent the 45 plaster surface, and means for attaching the box to said clamps.

5. In combination with a lath and plaster wall having an opening therethrough and having the plaster recessed about the opening in the laths, to expose the front side thereof adjacent the opening, an inner and an outer collar respectively engaged with back and front side of the laths about its opening and having means for clamping the 55 laths therebetween, said outer collar having outwardly projecting, plaster-retaining flanges, a box disposed in said collars, positioning means to locate the box with its outer end approximately at the level of the 60 plaster surface, and means for removably attaching the box to said outer collar.

In testimony whereof, I have signed my name to this specification.

JOHN J. MERRILL.
